UNITED STATES PATENT OFFICE

2,021,789

PURSE

Adolphe Krauss, Montreal, Quebec, Canada

Application August 7, 1933, Serial No. 683,961
In Canada August 11, 1932

8 Claims. (Cl. 150—28)

This invention relates to a purse of the reversible type.

An object of the invention is to so make a purse that it may be turned inside out when desired; by suitably lining the exposed parts of the purse with fabrics of different colors or patterns, either of the colors or patterns may be exposed to view by turning the purse inside out or outside in, as the case may be.

10 Another object of the invention is to so make the purse that it will conserve the appearance of the usual purse.

Another object of the invention is to improve on the purse shown in Canadian Patent No. 15 330,659, dated March 7, 1933, by substituting the end sliding fasteners by end frames which will permit of the purse being turned inside out or reversed, as and when desired. It is to be understood that while frames are shown in the present 20 drawings as a means of releasably locking the end walls, in lieu of the sliding fasteners shown in the said Canadian Patent No. 330,659 I claim the use either of frames which will permit of the purse operating as described, or of sliding fasteners.

25 Another object of the invention is to provide in such a reversible purse, a removable pocket or lining formed with compartments adapted to receive the objects usually carried in a lady's purse.

In the drawings, wherein like numerals of reference indicate corresponding parts in the various figures,

Figure 1 is a perspective view of the purse 35 when showing one color or pattern, the flap being open.

Figure 2 is a similar view to Figure 1 after the purse has been reversed or turned inside out to show the other color or pattern.

40 Figure 3 is an enlarged end view of Figure 1, but with one (the nearer) wall opened as in process of reversing the purse.

Figure 4 is an enlarged cross-section of the purse as on line 4—4 in Figure 1.

45 Figure 5 is an enlarged, fragmentary plan view of the purse when opened at the end walls, as in process of reversing the purse.

Figures 6 and 7 show details of construction of the end frames.

50 Figure 8 is a fragmentary, enlarged perspective view of one of the end frames.

Figure 9 is a side elevation of the removable pocket or lining.

55 Figure 10 is a section on line 10—10 in Figure 9.

Figure 11 is a fragmentary top plan view of Figure 9.

Referring now by numerals to the drawings, A indicates the purse complete, having a flexible member 10 adapted to bend and forming 5 when bent as shown (see Figure 1 for instance) the two side walls 11 and 12 of the purse. The member extends, as a part of one of the walls, 12, to form a flap 13 which bends downwardly over the purse in the usual way.

The flexible member 10 may be made as shown (see Figures 4 and 5), comprising a relatively stiff and thick piece of fabric 14, say leather, and linings 15 and 16 of another fabric, say corded silk, one on each side or face of the piece 14; 15 the linings 15 and 16 are of different colors or designs. The linings are extended at the ends, as at 17, to form when secured together along their edges, the end walls 18 of the purse. Between the linings 15 and 16 where they extend 20 as at 17, are secured relatively stiff and thick pieces 19 of some fabric, say leather, to give the necessary body or stiffness to the end walls of the purse. The member 10, as formed with the piece 14 and the double linings 15 and 16, and 25 as extended at the sides to form the two coacting wall portions 17A of the end walls 18, forms in effect one main, flexible member constituting the side walls, the end walls, and the flap of the purse complete. If a compartment 30 or pocket, capable of being opened and closed and locked closed, is to be provided, an extra ply 24 is applied to one side of the member 10, or more particularly on one of the linings, say 15. Between the member 10, or more 35 particularly the lining 15 and this extra ply 24, the pocket proper 25 may be secured, the pocket comprising two pieces 26 and 27 suitably secured or stitched as at 28. The extra ply 24 is preferably made of a piece 28A, of say leather, 40 and a lining 29, of say corded silk, the color of the silk being the same as that of the lining 15.

Preferably, the extra ply 24 extends over the width of the member 10 excepting the end wall portions 17A, but terminates short of the flap 45 where it is left unstitched, so that a handkerchief pocket 30 opening downwardly may be formed adjacent the part where the flap begins. Preferably, also, an extra ply 32 is secured on the other lining 16 of the member 10, extending 50 over the width of the member 10 excepting the end wall portions 17A, but terminating short of the flap, that is, similarly disposed with respect to the other ply 24. Thus, a handkerchief pocket 30A may also be formed, the pocket 30 aforesaid 55

being on one side of the member 10 and the pocket 30A being on the other side, all as best shown in Figures 1, 2 and 4. Where two extra plies 24 and 32 are used, one on each side of the member 10, the pieces 26 and 27 of the pocket 25 may be positioned between the extra ply 24 and the member 10, all as best shown in Figure 4. The extra ply 32 may also be formed with a piece 33 of leather and a lining 34 of the same colour or design as the lining 16. The pocket 25 may be opened and closed by sliding fasteners the complementary parts 35 and 36 releasably locked and unlocked by a slide 37.

On the flap 13 may be secured the female part 15 or socket 38, of suitable dome fasteners, adapted to register with and engage in the corresponding male part 39 secured to one side of the wall 11 of the purse, when the purse shows one color (see Figure 2), and to register with and engage 20 in a similar male part 40 mounted on a flexible tab 41 secured on the other side of the wall 11, of the purse (see Figure 1). Thus, where a flap 13 is used, such means provide for the locking of the purse closed, whether inside out or outside in.

The complementary parts of the sliding fasteners may be mounted on the purse according to the usual practice. For instance, the parts 35 and 36 may be secured to tapes 35A stitched 30 to the extra ply 24 and the main member 10, respectively (see Figure 4).

Preferably, a handle 42 is provided whereby to suspend the purse from the hand. The handle may take the form of an endless chain or cord 35 passing through the purse (or flap 13) as at 43 and 44. Thus, the handle may serve its purpose whether the purse be turned inside out, or outside in.

To releasably lock or secure the co-acting edges 40 of the end wall portions 17A, to thereby form the end walls 18 complete of the purse, sliding fasteners have been used in the purse shown in the said Canadian Patent No. 330,659. In lieu of such fasteners, I have substituted the frames 45 shown as B. These frames permit of the purse being turned inside out or outside in, as desired, while the hinged complementary parts 50 and 51 may be releasably locked at the top. The frame B, as shown, comprises the two members or legs 50 and 51 aforesaid, which are U-shaped in cross section to receive the adjacent edges of the co-acting end wall portions 17A so as to close over or clasp the wall portions. The two parallel flanges of the legs are cut transversely at the bottom 55 ends, as at 52, forming portions 53 which are curved in to receive the curved bracket portions 54 of the hinge members 55. The bracket portions 54 may be secured in position on the bottom of the legs, or more particularly on the curved 60 portions 53, as with rivets 56. The hinge members are formed with co-acting, flat eye portions 57 which are held in operative, hinged relation by a rivet or pin 58. Preferably, a washer 59 cut from solid rolled metal or punched out of steel 65 metal, is inserted between the eye portions.

Secured to the top of one of the legs, 50, is a latch device 60 adapted to releasably lock the two legs of the frame in closed relation. The latch device may comprise a hollow casing 61 adapted to be inserted onto the upper end of the leg and secured thereto as with rivets 62 passed through its side walls and through the parallel flanges, and having a bolt 63 spring-pressed and formed at the bottom 66 to engage in notches 64

formed in the upper ends of the parallel flanges of the other co-acting leg 51 of the frame.

The bolt or plunger 63 slides through the top wall of the casing and is provided with a head 65 to limit the downward travel of the bolt 5 under the action of a spring 67 mounted between the top wall of the casing and a collar 68 on the bolt. The casing is formed with downwardly extending portions 69, spaced to receive the upper portion of the leg 51 and prevent the same 10 from appreciable lateral movement.

It will be seen that such frames permit of the purse being reversed, as desired, that is, turned inside out, or outside in.

In order to protect the lining of the purse, a 15 removable lining or pocket, shown as at C, may be used. This pocket may be formed of fabric ends 70 and a celluloid member 71 bent to form the side walls 72 of the pocket. The member 71 may be secured to the ends 70 as by stitching 20 73. The upper edges of the side walls may be covered over as with a fabric tape 74 stitched to the sides as at 75. On one wall 72 may be provided a pocket 75A which is formed by applying a piece of fabric 76 and stitching the same 25 to the side wall, as at 77.

Operation

The purse is folded into purse shape and the legs of the end frames releasably locked together 30 by the spring latch device. The flap is closed by the dome fasteners. If the purse is to be reversed, or turned inside out, the latch is operated to release the two legs of the end frames, the main member (10) stretched out more or 35 less flat, the side wall portions 17A bent below the plane of the now-stretched main member so as to bring the frame members 50 and 51 below the plane of the main member, after which the wall portions 17A are swung inwardly or underneath the plane of the main member and this main member next folded to again bring the walls 11 and 12 into parallel relation, finally causing the frame members 50 and 51 to engage and lock.

What I claim is:—

1. In a reversible purse, a flexible member formed with a flap and adapted when folded into the shape of a purse to form the side and end walls thereof, co-acting means on the end walls 50 adapted to releasably lock said member in folded purse shape, and co-acting means on said flap and member adapted to releasably lock said flap to either side of one of said side walls.

2. In a reversible purse, a flexible member 55 formed with a flap and adapted when folded into the shape of a purse to form the side and end walls thereof, said member having contrasting opposite faces, co-acting means on the end walls adapted to releasably lock said member in folded 60 purse shape, and co-acting means on said flap and member adapted to releasably lock said flap to either side of one of said side walls.

3. In a reversible purse, a flexible member formed with a flap and adapted when folded into 65 the shape of a purse to form the side and end walls thereof, co-acting means on the end walls adapted to releasably lock said member in folded purse shape, a fastening element on said flap, and fastening elements on both faces of one of said 70 side walls alternatively receiving said first mentioned element whereby said flap may be releasably locked to either face of said side wall according as to whether said purse has been folded one way or the other.

4. In a purse as claimed in claim 3 said member having contrasting opposite faces.
5. A bag of the class described comprising a reversible body portion having different contrasting finish on opposite sides, reversible flexible extensions carried by opposite edges of said body portion, said body portion being foldable upon itself, channel members and bars carried by said extensions, said bars fitting within said channel members, and means for securing said bars within said channel members to releasably retain the sides of the bag in closed position.
6. A bag of the class described comprising a reversible body portion having different contrasting finish on opposite sides, flexible extensions carried by opposite edges of said body portion, said body portion being foldable upon itself, channel members carried by said extensions, bars fitting within said channel members, and spring 20 pressed members for securing the bars within said channel members.
7. In a reversible purse a reversible body por-

tion having different contrasting finish on opposite sides, reversible flexible extensions carried by opposite edges of said body portion, said body portion being foldable upon itself, members carried by opposite edges of said extensions and hinged at the bottom to draw said edges together when said members are brought into engagement and means for locking said members in engagement to thereby releasably retain the purse in closed position.

8. In a reversible purse a reversible body portion having different contrasting finish on opposite sides, reversible flexible extensions carried by opposite edges of said body portion, said body portion being foldable upon itself, members carried by opposite edges of said extensions adapted to be brought into substantial engagement, and means for releasably locking said members in substantial engagement to thereby releasably retain the purse in closed position.

ADOLPHE KRAUSS.
